Primary Examiner — Paula Greene(74) *Attorney, Agent, or Firm* — Birch, Stewart, Kolasch & Birch, LLP(57) **CLAIM**

The ornamental design for a portable earset case, as shown and described.

DESCRIPTION

FIG. 1 is a perspective view of the portable earset case showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof where the bottom plan view is a mirror image; and,

FIG. 7 is a perspective view showing the state that both earsets are detached from the subject design.

The broken lines in FIG. 7 show environmental structure only and form no part of the claimed design.
